(57) **CLAIM**

The ornamental design for a combined vacuum cleaner for pets, as shown and described.

DESCRIPTION

FIG. 1 is a front, top, right perspective view of a combined vacuum cleaner for pets showing our new design;

FIG. 2 is a back, left, bottom perspective view thereof;

FIG. 3 is a front view thereof;

FIG. 4 is a back view thereof;

FIG. 5 is an enlarged left view thereof;

FIG. 6 is an enlarged right view thereof;

FIG. 7 is a top view thereof;

FIG. 8 is a bottom view thereof;

FIG. 9 is an enlarged view of the encircled area 9 of FIG. 3;

FIG. 10 is an enlarged view of the encircled area 10 of FIG. 3; and,

FIG. 11 is an enlarged view of the encircled area 11 of FIG. 7.

The broken lines shown in the figures depict portions of the combined vacuum cleaner for pets that do not form part of the claimed design. The dot-dash lines depict the enlarged view boundaries that do not form part of the claimed design.

1 Claim, 11 Drawing Sheets
